(57) **CLAIM**

The ornamental design for a smart electric power socket track as shown and described.

DESCRIPTION

1. Smart electric power socket track

1.1 : Front

1.2 : Back

1.3 : Left

1.4 : Right

1.5 : Top

1.6 : Bottom

1.7 : Perspective

1.8 : Perspective

1.9 : Enlarged

1.10 : Enlarged

1.11 : Cross sectional

1.12 : Enlarged

1.13 : Enlarged

Reproduction 1.9 is an enlarged view of the Reproduction 1.3; Reproduction 1.10 is an enlarged view of the Reproduction 1.4; Reproduction 1.11 is a cross sectional view taken along line “B-B” of the Reproduction 1.1; Reproduction 1.12 is an enlarged view of the encircled portion “c” of the Reproduction 1.1; Reproduction 1.13 is an enlarged view

(Continued)

of the encircled portion "d" of the Reproduction 1.4; The broken lines shown in the drawings illustrate portions of the smart electric power socket track that form no part of the claimed design.

1 Claim, 13 Drawing Sheets
